CLAIM

The ornamental design for a child's feeding spoon or the like, as shown and described.

DESCRIPTION

FIG. 1 is a top plan view of a child's feeding spoon or the like showing my new design;
FIG. 2 is a front elevational view thereof;
FIG. 3 is a bottom plan view thereof;
FIG. 4 is a rear elevational view thereof;
FIG. 5 is an elevational view as seen from the left of FIG. 2;
FIG. 6 is an elevational view as seen from the right of FIG. 2;
FIG. 7 is an elevational view as seen from the left of FIG. 1; and
FIG. 8 is an elevational view as seen from the right of FIG. 1.
